UNITED STATES PATENT OFFICE.

GEORGE P. BOSWORTH, OF PAWTUCKET, RHODE ISLAND.

ROLLER-SKATE.

SPECIFICATION forming part of Letters Patent No. 331,470, dated December 1, 1885.

Application filed October 6, 1884. Serial No. 144,861. (No model.)

To all whom it may concern:

Be it known that I, GEORGE P. BOSWORTH, of Pawtucket, in the county of Providence and State of Rhode Island, have invented an improvement in Roller-Skates, of which the following is a specification.

My invention has reference to that class of roller-skates in which the foot-plate can be tipped or inclined by the movement of the foot of the wearer, so as to cause the axles of the wheels or rollers to change from a parallel to an inclined position with relation to each other, and thus cause the skate to run in a curved line; and my invention consists in the improved construction of the hangers and hanger-bearings for the axles of the rollers, as hereinafter fully set forth.

Figure 1 represents an elevation and partial section of my improved skate, the left-hand forward roller being removed in order to show the slot of the hanger. Fig. 2 is a plan view of the under side of the skate, the rear right-hand roller being shown in section, and the adjacent portion of the hanger broken away in order to show the bearing-piece for the roller-axle and the inclosed rubber spring. Fig. 3 is a perspective view of the bearing-piece for the roller-axle.

In the accompanying drawings, A is the foot-plate of the skate, to the under side of which are secured the inclined hangers B B, made in separate halves *a a*, which are each provided with an inclined recess, *b*, thus forming a chamber adapted to receive and guide the flanged central portion, *c*, of the bearing-piece C, and also to receive the rubber spring D. The contracted ends of the bearing-piece C are made to project through the inclined slots *d* in the sides of the opposite portions *a a* of the hanger, and the said opposite portions are secured to each other by means of the screw *e*. The front and rear hangers are secured to the foot-plate in an oppositely-inclined position by means of the flanges *ff*, the slots *d d* of the hangers preferably forming an angle of about forty-five degrees with the bottom of the foot-plate. The rubber spring D is held within the recess

b b of the hanger above the flanged side of the bearing-piece C, the shoulders *g g* of the flanges serving to prevent the bearing-piece from being moved in an endwise direction when held within the inclosed chamber of the hanger. The axle E is held loosely within the bore of the bearing-piece C, and the rollers F F are loosely held upon the axle E by means of the linchpins *h h*. When the foot-plate A is held in a horizontal position, the axles E E of the rollers will be held parallel to each other; but when the foot-plate is inclined to either side the inclination of the hangers and action of the spring D upon the flanged bearing-piece C will cause the axles E E to converge at the side toward which the foot-plate is inclined, thus causing the skate to roll in a curved line, as desired.

I am aware that it is not new to provide inclined hangers for the axle-bearings of roller-skates, and that it is not new to provide the hangers with an inclined slot which serves to guide the axle-bearing. I therefore make no claim to such construction, but only to the special form and arrangement of the several parts, as shown and described.

I claim as my invention—

1. In a roller-skate, the combination of the foot-plate with the longitudinally-inclined hanger B, made in two oppositely-arranged parts, *a a*, provided with attaching-flanges *f*, inclined recess *b*, and a slot *d*, with the flanged bearing-piece C, provided with the guiding-shoulders *g g*, the rubber spring D, axle E, and rollers F F, substantially as described.

2. In a roller-skate, the combination of the foot-plate with the oppositely-inclined front and rear hangers, made in two oppositely-arranged parts, *a a*, provided with the attaching-flanges *f*, and having the inclined recesses *b* and slots *d*, with the flanged bearing-pieces C, provided with the guiding-shoulders *g g*, the rubber springs D, axles E, and rollers F, substantially as described.

GEORGE P. BOSWORTH.
